PROCESS AND APPARATUS FOR CUTTING
AND FOLDING FABRIC STRIPS

Frans Gerard Carel Margadant, Bergen op Zoom,
Netherlands, assignor to Stoombandfabriek N.
V. van Engelen & Evers, Heeze, Netherlands, a
corporation of the Netherlands

Application October 3, 1940, Serial No. 359,625
In the Netherlands November 7, 1938

4 Claims. (Cl. 270—61)

The invention relates to a process and apparatus for mechanically treating a woven tape, in which the tape is cut in transverse direction and the two ends thereby produced are folded in one operation, parallel or almost parallel to the cut.

The articles thereby produced have to serve in particular as labels, adapted to be attached to various ready-made clothes or other dresser's workpieces by means of a stitching in the folded portion.

In the known process referred to above the folded ends of the cut piece of tape are not positioned in flat condition against the piece of tape itself, which, however, is desirable for the further treatment (packing and sewing on) of the piece of tape.

Now, the invention consists in this that the folding of the tape-ends is effected by so pressing each end over the full width and to such an extent into a slot-shaped space of a work table that that end is folded U-like within the slot.

The result thereof is that the folded ends of each piece of tape is pressed flat against the remaining portion of the tape for the reason that the fold is produced in the slot itself. An apparatus for carrying out the novel process includes a work table, a cutting member operating in a direction perpendicular to said table and two folding members located at either side of said cutting member and also operating in a direction perpendicular to said table, said folding members cooperating with corresponding slot-shaped spaces in the work table. According to the invention the distance of each of the folding members cooperating with corresponding slot-shaped length of the path through which the folding member is moved in the slot.

Consequently each cut end of the piece of tape is not pressed into the slot in flat condition but it keeps its U-shape when the folding member is withdrawn from the slot.

In order to produce in the slot a sharp fold one of the lateral walls of each slot-shaped space in the work table may be laterally movable and the folded tape end compressed thereby. In order to increase this effect a heating means may, according to the invention, be located in one lateral wall or in both lateral walls of the slot-shaped space.

The invention will be described more fully hereinafter with reference to the accompanying drawings, illustrating by way of example and schematically the essential means for carrying out the process, the position of the work table

being horizontal, and a practical embodiment of a machine according to the invention.

Figures 1, 2, 3 and 4 show different positions of the cutting and folding means.

5 Figure 5 is a schematical side-elevation of an operating mechanism.

Figure 6 is a front elevation thereof.

Figure 7 is a side elevation of a machine according to the invention.

10 Figure 8 is a partial front elevation thereof.

Figure 9 shows a structural detail and

Figure 10 shows another detail.

Above a work table 1 a vertically movable knife 2 is arranged, cooperating with a stationary knife 3 underneath said table. Further there are provided two vertically movable folding members 4, one at either side of the knife 2, and two vertically movable pressure members 5, one at the exterior of each of the folding members.

20 The work table is provided with three slots 6, 7 and 8; the central slot 7 offers an opportunity for the passage of the knife 2; the slots 6 and 8 are adapted to cooperate with the folding members 4.

The parts 9 and 10 of the work table are hollow and are internally provided with a (non-illustrated) heating means; the parts 11 and 12, forming the vertical outer walls of the slots 6 and 8, are laterally movable so that they are adapted to be pressed against the heated walls 9 and 10.

Figure 1 shows the position in which a tape is lying on the work table and the various vertically movable members have been moved downwards to such an extent, that the pressing members 5 will clampingly hold the lint on the table. In the course of the continued downward movement the knife 2 cuts the tape and immediately

30 thereafter the folding members 4 will press the two tape ends at the left and at the right of the cut into the slots 6 and 8 (see Fig. 2).

During the following upward movement the vertically movable members reach the position 40 shown in Figure 3. In this position the members 11 and 12 have been moved to the right and to the left respectively and have compressed the tape, folded in U-shape, in each of the slots 6 and 8.

50 In the final position according to Figure 4 the pressing members 5 also have been removed from the tape and the parts 11 and 12 have been returned in their original position.

Assuming that the tape is supplied from the 55 left (Fig. 4) then in said final position one cut

and folded tape portion (e. g. a label) 13 may be removed from the machine while the end 14 of the tape coming from the left has been folded. The operation may then be repeated as indicated in Fig. 1. When applying the process to labels, woven in the shape of a tape, it will be clear that a mark may be provided on the lower side of the tape, whereby it is possible to cut the lint always at the correct place between two labels.

In Figures 5 and 6 the same parts, shown in Figures 1-4, are again shown, however in cooperation with a schematically shown operating mechanism.

The elements 2 (knife) and 4 (folding members) by means of a yoke 18 are together secured to a rod system 15 that by means of an unround disc 16 and a lever 17 is vertically reciprocated.

The pressing members 5 are secured to a lever 19 having its fulcrum at 20 and being normally kept down by a spring 21 in a position, in which the pressing members hold the tape on the work table. In the course of the upward movement of the members 2 and 4, however, the lever 19 is moved upwardly by means of a roller 22 adapted to engage a stop 23 on said lever.

The members 11 and 12 are mounted on two pivotal levers 24, 25. Springs 29 serve to keep normally closed the slots 6 and 8. Cams 26, 27 on the levers cooperating with rollers 28 on the rod system 15 take care that the slots 6 and 8 are always opened in time for the passage of the folding members 4.

The unround disc 16 should of course have such a configuration that during the rotation the various manipulations are always effected at the proper time.

In the machine according to Figures 7, 8, 9 and 10 a plurality of cam discs are mounted on a driving shaft 33, said cam discs controlling the movement of the various members 2 (the knife), 4 (the two folding members), 5 (the two pressing members) and 11 and 12 (the two lateral walls of the slot).

The central cam disc 31 cooperating with the roller 32 is adapted to move the knife 2. To this end the knife is rotatably mounted on a shaft 33 and the knifeholder 34 is extended to form a lever 35 carrying the roller 32. The end 36 of said lever is provided with a pressing piece 37 on which is bearing a roller 38. This roller is mounted in another double-armed lever 39 having its fulcrum at 40 and being provided at one end with an adjustable pressure screw 41. This screw is kept in engagement with a roller 42 attached to a vertically movable slide 43 acting as a guide means for the two folding members 4. The bell crank lever 44 and the opening 45 serve to normally keep upwards the folding members, outside the slots.

At either side of the cam disc 31 two cam discs 46 are mounted on the driving shaft 33, said cam discs 46 moving the two pressing members 5 by means of rollers 47, in engagement with said discs, and levers 48. A buffer 49 on each of the levers 48 and bearing against a set of leaf springs 50 serves to normally keep the pressing members 5 in pressure engagement with the work table.

Finally, at either side of the cam discs 46, two cam discs 51 are mounted on the shaft 33 to move the lateral slot walls 11 and 12. Each of said cam discs 51 cooperates with a roller 52 on a lever

53 having its fulcrum at 54. The end of the lever 53 is constituted by a holder 61 for a slot wall 11 and 12 respectively, shown for the sake of clearness in section and hatched (Figure 8).

5 By means of a pressure spring 55, supported in the machine frame, the lever 53 is rotated anti-clockwise, i. e. the roller 52 is kept pressed against the cam disc 51 and the slot 12 is kept normally closed (as indicated in Figure 8). A heating element 56 is located in the interior of the movable wall of the slot. This is a modification in comparison with Figures 1-4, in which the heating element is located within the hollow stationary wall 10 of the slot.

10 13 As regards the movement of the knife 2 reference is directed to Fig. 9 in which the knife 2 and its holder 34 and the lever 35 are shown separately. In order to ensure that the knife is normally kept lifted in a non-cutting position, a second lever 57 is rigidly connected with the holder 34.

20 The end of said second lever 57 is connected to the machine frame by means of a spring 58. Moreover the knife is adapted to perform a rotation about a shaft 60 under the influence of a torsion spring 59 so that the cutting edge is always pressed against the stationary lower knife 3.

I claim:

1. A process for treating a tape comprising cutting said tape transversely and then simultaneously pressing the ends of the tape so cut throughout the entire width thereof substantially parallel to the cut into slot-shaped recesses provided in a work table so as to form at each end a folded portion of U-shape in each slot.

2. A machine for treating a tape comprising a work table having slot-shaped recesses therein, a cutting member operating perpendicular to said table, a folding member located at each side of said cutting member and also movable perpendicular to said table, each folding member cooperating with a slot-shaped recess in said table and the distance of each of said folding members from said cutting member being greater than the length of the path of movement of said folding member in its cooperating recess.

3. A machine for treating a tape comprising a work table having slot-shaped recesses therein, a cutting member reciprocating perpendicular to said table, a folding member located at each side of said cutting member and also reciprocating perpendicular to said table, a clamping member for clamping said tape to said work table located adjacent each folding member and at the said thereof opposite to said cutting member, said pressing members also being reciprocable perpendicular to said table so that said tape may be clamped to said work table during the cutting and folding operations.

4. A machine for treating a tape comprising a work table having slot-shaped recesses therein, a cutting member reciprocable perpendicular to said table, a folding member located at each side of said cutting member and vertically reciprocable relative to said table and cooperating with a correspondingly shaped recess in said work table, a lateral wall located adjacent each of said recesses and means for laterally moving each wall so that a doubled end of said tape located within a recess may be compressed.

FRANZ GERARD CAREL MARGADANT.
